ATTORNEY

UNITED STATES PATENT OFFICE

ALBIN LESSING, OF BROOKLYN, NEW YORK

PICTURE DISPLAYING VANITY BOX

Application filed September 18, 1930. Serial No. 482,670.

This invention relates to new and useful improvements in a picture displaying vanity box.

The invention has for an object the provision of a picture displaying vanity box with a disc rotatively mounted within an inner chamber and formed with a plurality of adjacent transparent pictures arranged concentric with its rotation point and selectively viewable through an opening, and means for limiting turning of the disc in one direction so as to see an orderly sequence of the pictures when viewed through the opening.

15 The invention also proposes the provision of ratchet teeth upon the said disc engageable by a pawl finger on a lever projecting to the exterior and movable for accomplishing the turning of the disc in one direction.

20 A further object of this invention is to provide a means for adjusting the pivoting limits of said lever so that upon one full stroke consecutive or alternate pictures may be seen through the opening.

25 The invention has for a further object the provision of a device of the class mentioned which is of simple durable construction, dependable in use and efficient in action, and 30 which can be manufactured and sold at a reasonable cost.

35 For further comprehension of the invention, and of the objects and advantages thereof, reference will be had to the following description and accompanying drawings, and to the appended claims in which the various novel features of the invention are more particularly set forth.

40 In the accompanying drawings forming a material part of this disclosure:—

Fig. 1 is a perspective view of a device constructed according to this invention.

Fig. 2 is a sectional view taken on the line 2—2 of Fig. 1.

45 Fig. 3 is a fragmentary enlarged sectional view taken on the line 3—3 of Fig. 1.

Fig. 4 is a horizontal sectional view taken on the line 4—4 of Fig. 2.

50 Fig. 5 is a fragmentary sectional view taken on the line 5—5 of Fig. 4.

Fig. 6 is a fragmentary sectional view taken on the line 6—6 of Fig. 1.

Fig. 7 is a horizontal sectional view taken on the line 7—7 of Fig. 6.

Fig. 8 is a view similar to Fig. 7, but showing the parts in a different position of adjustment.

The picture displaying vanity box comprises a shell consisting of several layers indicated by reference numerals 10, 11 and 12 and forming a flat chamber 13 and each of said shell sections having a small opening 14 aligned with each other so that one may look through a portion of the chamber 13, a disc 15 rotatively mounted in the chamber 13 and supporting a plurality of adjacent transparent pictures 16 on a circle concentric with the point of rotation of the disc and selectively viewable through the small openings 14, ratchet teeth 17 on said disc 15 and on a circle concentric with the axis of the disc, a lever 18 pivoted on the axis of the disc, and extending through slots 19 in said shell and having a resilient pawl finger 20 engaging said ratchet 17 for turning the disc in one direction only, and means for adjusting the pivoting limits of said lever 18 so that upon one full stroke consecutive or alternate pictures 16 may be seen through the openings 14.

80 The shell sections 10, 11 and 12 comprising the shell constitutes respectively an outer, an intermediate, and an inner shell. The outer shell 10 is formed with a curved bottom 21 and is opened at the top. The intermediate shell 11 is formed with a flat bottom 22 and is also opened at the top and fits tightly within the outer shell section. Preferably, it should be raised or soldered against displacement. The inner shell section 12 is formed with a flat top 23 and is opened at the bottom, and the chamber 13 is formed between the top 23 of the inner shell section and the bottom 22 of the intermediate shell section. Peripheral transverse projections 24 extend inwards from the vertical sides of the intermediate shell section 11 and engage into corresponding grooves in the inner shell section 12 so as to hold these shell sections in relative positions restraining them from turning so

that the openings 14 are at all times in line. The inner shell section 12 may be removed so that access may be had to the disc 15 which is within the chamber 13.

5 The rotative mounting of the disc 15 is accomplished by a pin 25 projecting from the bottom 22 of the intermediate shell section 11 and engaging into an opening in the bottom of the disc 15. The head of the pin 25 is hid 10 from view in that it is disposed in the space between the bottom 22 of the intermediate shell section 11 and the bottom 21 of the outer shell section 10. The disc 15 is formed with a top circular recess 26 having an internal periphery 15 groove so as to receive a stiff flexible transparent disc 27 upon which the pictures 16 are formed. These pictures may be photographs developed directly upon sensitized material engaged on the transparent 20 disc, or may be photographic films pasted or otherwise cemented in place upon the disc. The disc 15 is formed with a plurality of window openings 28 for each of the pictures 16 so that there is an unrestricted view through 25 the pictures. The lever 18 has a central enlarged portion constituting a hub which is pivotally engaged upon the pin 25, and has a reduced shank portion 29 which extends through the slots 19. At the outer end the 30 lever 18 is formed with a head portion 30 for manual moving of the lever.

The means for adjusting the pivoting limits of the lever 18 so that upon full stroke consecutive or alternate pictures may be seen 35 through the openings 14 comprise a lever section 31 consisting of a shank portion 32 connected with a head portion 33. The shank portion 32 is pivotally connected by a rivet 34 upon the shank portion 29 of the lever, 40 while the head portion 33 is formed with projections 35 engaging in corresponding niches in the lever head 30 so that the lever section 31 is maintained in a fixed position. The projections 35 are so spaced that the lever section 45 31 may be moved to the position indicated by the dot and dash lines 36 in Fig. 4 and in this condition the position is maintained by certain of the projections 35 engaging in the niches in the head 30, and at the 50 same time the amplitude of possible motion of the lever 18 is changed in that the slots 19 are of fixed size while the portion of the lever passing through the slots has been changed.

A tube 37 projects from the top 23 of the 55 inner shell section 12 and encircles the opening 14 in this particular part. This tubular element is formed with several splits so as to frictionally receive and hold another tube 38 which supports a lens 39. A person looking 60 through the lens sees the picture and upon changing the relative telescopic relations of the tubes 37 and 38, the lens may be focused to the person's eye. The inner shell section 12 is of smaller height than the intermediate 65 shell section 11 so that there is a space above

it and between the top edge of the shell section 11. In this space a container 40 engages. A cake of powder 41 is held by the container 40 and above this a powder puff 42 is placed so that the powder may be used. The container 70 40, the cake of powder 41, and the powder puff 42 are all formed with a cutout 43 so as to encircle the tubular member 37, whereby the tubular member may extend materially above these parts.

75 As illustrated on the drawing, a cover 44 is hingedly connected upon the outer shell 10 and serves to cover this shell so as to form the vanity box. A mirror 45 is mounted within the cover and thus held by a washer 46. The mirror 45 is formed with a cutout 47 for making additional room for the tubular members 37 and 38 when the cover 44 is in a closed position upon the outer shell. A catch is provided for holding the cover in a closed condition and comprises a spring element 48 mounted upon the shell 10 and having a finger piece 49 for slight movements and engageable with a bent portion 50 upon the cover 44 so as to hold these parts together. 80

85 The operation of the device may be traced by assuming it in the condition as shown in Fig. 1. For novelty reasons a person may look through the lens 39 and view the particular picture exposed through the openings 14. Then the handle 30 may be drawn across the slot 19 one complete stroke so as to cause the disc 15 to turn slightly and expose alternate pictures to view through the openings 14. In this manner alternate pictures may be viewed in consecutive order. To view consecutive pictures, it is merely necessary to force the head portion 30 and the portion 33 of the lever section 31 apart so that the lever section may be moved to the position indicated by the dot and dash lines 36 in Fig. 4. Now, when the lever is moved one complete stroke by moving the head element 30, the disc 15 will be turned so as to expose consecutive pictures. 95

100 The powder puff 42 and the powder 41 may be used as is conventional together with the mirror 45. To close the case, it is first necessary to collapse the tubular member 38 into the member 37 so as to take up a minimum amount of space. Then the cover 44 can be closed down and will thus be held by the catch. 105

110 While I have shown and described the preferred embodiment of my invention, it is to be understood that I do not limit myself to the precise construction herein disclosed and the right is reserved to all changes and modifications coming within the scope of the invention as defined in the appended claims. 115

120 Having thus described my invention, what I claim as new, and desire to secure by United States Letters Patent is:—

125 1. A shell consisting of several shell sections forming a flat chamber and each of 130

- the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings.
2. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings, the rotative mounting of the disc being accomplished by a pin engaged through one of the sections of the shell and engaging in an aperture in the center of the disc.
3. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings, said shell sections comprising an outer section with a closed bottom and an open top firmly holding an intermediate section with a closed bottom and an open top which in turn firmly holds an inner section with a closed top and an open bottom for forming the said chamber.
4. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings, the rotative mounting of the disc being accomplished by a pin engaged through one of the sections of the shell and engaging in an aperture in the center of the disc.
5. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings, said lever comprising a large hub portion and a thin shank extending through said slots and terminating outside in a large head.
6. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc

and extending through slots in said shell and having a resilient pawl finger engaging said ratchet teeth for turning said disc in one direction only, and means for adjusting the pivoting limits of said lever so that upon one full stroke consecutive or alternate pictures may be seen through said openings, said lever comprising a large hub portion and a thin shank extending through said slots and terminating outside in a large head, said means for adjusting the pivoting limits of the lever comprises a lever section consisting of a shank portion pivotally connected with said shank portion and firmly connected with a head portion having projections engaging niches formed in the said large head portion.

7. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, means for adjusting the pivoting limits of said lever so that upon one full stroke consecutive or alternate pictures may be seen through said openings, a container holding a cake of powder and engaged within said shell, and a cover for closing the shell.

8. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, means for adjusting the pivoting limits of said lever so that upon one full stroke consecutive or alternate pictures may be seen through said openings, a container holding a cake of powder and engaged within said shell, and a cover for closing the shell, said cover supporting a mirror.

9. A shell consisting of several shell sections forming a flat chamber and each of the shell sections, having a small opening in line with each other so that one may look through a portion of said chamber, a

disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, said shell sections comprising an outer section with a closed bottom and an open top firmly holding an intermediate section with a closed bottom and an open top which in turn firmly holds an inner section with a closed top and an open bottom for forming the said chamber.

10. A shell consisting of several shell sections forming a flat chamber and each of the shell sections having a small opening in line with each other so that one may look through a portion of said chamber, a disc rotatively mounted in said chamber and supporting a plurality of adjacent transparent pictures on a circle concentric with the point of rotation of said disc and selectively viewable through said small openings, ratchet teeth on said disc and on a circle concentric with the axis of said disc, a lever pivoted on the axis of said disc and extending through slots in said shell and having a resilient pawl finger engaging said ratchet teeth for turning said disc in one direction only, said shell section comprising an outer section with a closed bottom and an open top firmly holding an intermediate section with a closed bottom and an open top which in turn firmly holds an inner section with a closed top and an open bottom for forming the said chamber, transverse peripheral ridges projecting from the intermediate section and engaging in corresponding grooves in the inner section so as to hold these parts against relative turning.

In testimony whereof I have affixed my signature.

ALBIN LESSING.
